FLUORESCENT TUBE OR SIMILAR ARTICLE

Mike Tecton, 5101 45th St. NW,
Washington, D.C. 20016

Filed Sept. 3, 1965, Ser. No. 86,824

Term of patent 14 years

(Cl. D26—8)

FIG. 1 is an end, top and side perspective view of a fluorescent tube or similar article, showing my new design;

FIG. 2 is an opposite end, bottom and opposite side perspective view;

FIG. 3 is a cross-sectional view thereof, to an enlarged scale, taken on line 3-3 in FIG. 2;

FIG. 4 is a side elevational view, the opposite side being substantially a mirror image thereof; and

FIG. 5 is an end elevational view thereof, to an enlarged scale, the opposite end being substantially a mirror image thereof.

I claim:

The ornamental design for a fluorescent tube or similar article, substantially as shown and described.
